UNITED STATES PATENT OFFICE.

FREDRICK H. AULD, OF COLUMBUS, OHIO.

ORNAMENTAL ARTICLES OF MANUFACTURE AND METHOD OF PRODUCING THE SAME.

Application filed August 27, 1928. Serial No. 131,975.

This invention relates to improvements in ornamental articles of manufacture and to the method of producing the same.

The object of the invention is to ornament articles of manufacture such as furniture, radio cabinets, musical instruments, etc., by combining a part of such structures, such as a desk top, with an inlaid design comprised of a metal plate containing the design itself and a veneer of wood inlaid in the design, the desk top in the illustration here given forming the base with which the metal design and the veneer will be incorporated.

The invention further consists in the method by which this article is fabricated as will be hereinafter fully stated.

In the accompanying drawings

Figure 1 is a plan view of say a desk top with my invention applied thereto;

Figure 2 is a sectional view;

Figure 3 is a plan view of the metal plate showing the design;

Figure 4 is a sheet of veneer;

Figure 5 is an inverted plan view of the metal plate and the veneer;

Figure 6 is a top plan view of the veneer and the design;

Figure 7 is a sheet of celluloid.

Let it be supposed that a desk top is to be ornamented with an inlaid design. Such a top is indicated at 1 in the drawings, as best seen in Figure 1. On this top I mount a sheet of veneer, composed of one or more pieces as may be needed. This sheet is indicated at 2.

Before the veneer is applied to the desk top the design shown in Figure 1 is fabricated. This design is shown in Figure 3 where a plan view is given of a metal plate 3 having a design wrought thereon either by the use of a die by which to stamp the design on the metal plate or by the well known process of etching the design into the plate. In either case the plate is ornamented with the design as clearly seen in Figure 3.

In Figure 4 we have illustrated a sheet of veneer of wood representative of the veneer that is to be inlaid in the design and to be applied to the top of the desk in the example here being given. In Figure 5 we have illustrated an inverted plan view of the metal plate and the veneer after they have been joined together by one of the steps of the method.

In Figure 6 I have shown a top plan view looking down on the veneer with the de-

sign faintly appearing in the veneer in the state which precedes the step of dressing off the wood to expose the tracery of the design with the wood left in the depressions 60 surrounding the tracery.

When the article has been completed it will take on the appearance indicated in Figure 1 where the top of the desk is shown with the design wrought in metal and inlaid with wood and the veneer applied to the top.

Thus it will be seen that the article comprises as its base a part of the furniture or other structure, the wood veneer overlying the top and the metal design plate occupying a place between the top and the overlying veneer, with that part of the veneer which overlies the tracery of the design removed to expose the design, and with that part of the veneer which is over the depressions surrounding the tracery inlaid down in such depressions.

I will refer now to my method of producing this article. I assume that the desk top or other structure to be ornamented has been prepared and is ready for the application of the veneer and the design. The particular design having been decided upon it is wrought in the metal plate 3 either by the use of a die containing the design or by the use of the well-known etching process by which the design can be formed on the plate. This being done the metal plate is treated to a light deposit of latent celluloid solvent such as camphor (applied either by deposit from a volatile solution or by sublimation) and a sheet of dry celluloid is superimposed upon the treated metal. Then the wood veneer which has also been previously treated with a solvent such as butanol, is placed upon the celluloid sheet which now lies on the metal plate. The metal plate, the celluloid and the veneer being now together are placed in a press and subjected to heavy pressure, such as 800 to 1000 pounds per square inch for a period of from ten to fifteen minutes, accompanied by heat applied to the press so as to produce a temperature of from 115° C. to 125° C. in the plate, celluloid and veneer.

The result of these steps is to depress the veneer into the design to give the appearance shown in Figure 6 where the veneer is represented as having been depressed into the recesses about the tracery of the design and to overlie the raised surface constituted

by the tracery. And at the same time that this is being affected, the solvents and the heat acting on the celluloid will have reduced the faces thereof to a gummy or sticky state, whereby it constitutes a most effective adhesive between the metal plate and the wood veneer.

Then the now composite article is withdrawn from the press and the face of the veneer ground or dressed off to the extent necessary to remove the wood from above the tracery of the design so as to expose the design and leave the wood around the design and in the depressions between the lines of tracery.

This condition is shown in the finished product represented in Figure 1 where the design is shown inlaid with the veneer and where the veneer and the metal plate have been united to the desk top. The method of uniting the veneer and the metal plate may be the usual one of uniting veneers to furniture such as by the use of an adhesive and a suitable pressure to effect the union of the veneer and the top.

Again, the back of the metal plate, in order to prevent any undue excrescence of it beyond the veneer surface, is either dressed off to reduce the thickness of the plate so that there will be no appreciable excrescence formed by it, or the plate is originally very thin, say of a thickness of not exceeding or less than that of the veneer itself, except that part of the plate which is constituted of the tracery of the design which, of course, must be thick enough to allow the design to stand out in relief in order that the wood may be inlaid down in the spaces about the tracery.

It will now be seen that by my method I am enabled to beautifully and cheaply ornament various articles of manufacture with inlaid work, and that the resulting product comprises as the base of the article the structure to be ornamented, as the desk top, the hidden metal plate with its design wrought thereon and the veneer, which in part is inlaid in the design and as to the remainder forms the finished surface of the article.

It will be understood that I desire to comprehend within my invention such modifications as may be necessary to adapt it to varying conditions and uses.

Having thus fully described my invention what I claim as new and desire to secure by Letters Patent, is:

1. The herein described product, consist-

ing of an article of manufacture a part of which comprises a base; a metal plate wrought with an ornamental design and a veneer of wood overlying the article and the plate, inlaid in the depressions about the design and removed over the tracery to expose the design, the wood and metal being united by a binder of celluloid.

2. The herein described product, consisting of an article of manufacture a part of which comprises a base, a metal plate wrought with an ornamental design, an adhesive on the face of the plate including the design, and a veneer of wood overlying the article and the plate with the adhesive intervening, and inlaid in the depressions about the design and removed over the tracery to expose the design, the wood and metal being united by a binder of celluloid.

3. The herein described method of ornamenting an article of manufacture, consisting in preparing the part of the article to be ornamented to constitute a base; in coating the said piece with a solvent for celluloid; in fabricating a design on a metal plate; in coating the metal with a solvent for celluloid; in placing a sheet of celluloid between the metal and veneer; in laying in the design a wood veneer by the application of pressure; in dressing off the portions of the veneer which overlie the tracery of the design to expose the design and leave portions of the veneer inlaid in the depressions around the design; and in applying and securing the veneer with its incorporated design to the surface of the article to be ornamented.

4. The herein described method of ornamenting an article of manufacture, consisting in preparing that part of the article which is to be decorated; in fabricating a design on a metal plate; in applying to the plate an adhesive comprising celluloid; in overlaying the plate with its adhesive with a wood veneer; in subjecting these parts to pressure and heat to force the veneer into the depressions in the plate which surround the design and partially bulge the tracery of the design through the veneer; in later dressing off those portions of the veneer which so overlie the tracery to expose the design and leave the veneer inlaid about it; and in applying and securing the veneer with its contained design to the surface to be ornamented.

In testimony whereof, I affix my signature.

FREDRICK H. AULD.
